CENTRIFUGAL CONTROL

Joseph H. Staley, Columbus, Ind., assignor to
Electric Switch Corporation, Columbus, Ind., a
corporation of Indiana

Application May 17, 1937, Serial No. 143,087

25 Claims. (Cl. 200—80)

My invention relates to a centrifugal control adapted for operative association with rotary machines generally for the purpose of controlling the speed of the associated or other machines, and the operation of mechanical and electrical devices generally, including the making and breaking of electric circuits, and is particularly concerned with providing a control having a mercury switch or generally a switch of the fluid flow type as the centrifugally operated member. Mercury switches have heretofore been centrifugally controlled to determine various conditions of operation. These previous embodiments have generally taken the form of a rockable or rotatable mercury tube switch which is actuated by a remote, centrifugally controlled member, or a switch which is rotated about its axis to displace the mercury along the sides of the tube, or a switch which is fixed in position relative to a support carried by a rotary shaft, for example. In the latter case, the switch tube is usually inclined to the shaft.

Such switch constructions, however, are characterized by sluggishness, jerkiness and irregularity in operation and are incapable of being finely governed, particularly where used to control the speed of rotary machines, such as electric motors. Under the latter condition, the motor tends to fall into a state of speed oscillation, or so-called "hunting," in which the governor fluctuates over a wide range in its endeavor to "find" the desired speed. Where the maintenance of a definite speed within close limits is a condition of operation, such fluctuation is undesirable. It is therefore one object of my invention to devise a centrifugal control employing a mercury switch which is characterized by a greater sensitivity and fineness of control relative to existing devices intended for the same character of operation.

A further object is to provide a control of the character indicated in which the mercury switch is at all times, during the operation of the associated machine, subjected to a resilient restraint that is independent of the centrifugal force acting on the switch.

These and further objects of my invention will be set forth in the following specification, reference being had to the accompanying drawings, and the novel means by which said objects are effectuated will be definitely pointed out in the claims.

In the drawings:

Fig. 1 is an enlarged, sectional elevation of one form of my improved control.

Fig. 2 is a sectional view, taken along the line 2—2 in Fig. 1, looking in the direction of the arrows.

Fig. 3 is a vertical, sectional elevation of a modified type of control.

Fig. 4 is a section along the line 4—4 in Fig. 3, looking in the direction of the arrows.

Fig. 5 is a sectional elevation showing another modification of my improved control.

Fig. 6 is an elevation of the upper portion of the control, as viewed in Fig. 5.

Figs. 7 and 8 are sections along the lines 7—7 and 8—8, respectively, in Fig. 6, looking in the direction of the arrows.

Fig. 9 is a section along the line 9—9 in Fig. 5, 16 looking in the direction of the arrows.

Fig. 10 is a sectional elevation of a further modification of my improved centrifugal control.

Fig. 11 is a sectional plan view taken along the line 11—11 in Fig. 10, looking in the direction of 20 the arrows.

Fig. 12 is a fragmentary, elevation view, looking in the direction of the arrow 12 in Fig. 10, and showing the use of a torsion spring to control the mercury switch.

Referring to Figs. 1 and 2 of the drawings which illustrate one structural arrangement of my improved centrifugal control, the numeral 11 designates a shaft, or generally any rotary member, which is shown in a vertical position, 30 although the control may be located horizontally when used with a horizontal shaft, or in any position intermediate a horizontal and vertical position. The control, denoted generically by the numeral 12 in Fig. 1, is mounted on the 35 upper end of the shaft 11, as presently described.

Referring more particularly to Fig. 1, the control 12 includes a disk 13 having a hub 14 depending from the underside thereof which is provided with a threaded extension 15 that is 40 fixedly mounted in the upper end of the shaft 11.

A block 16, preferably composed of insulating material, is fixedly mounted on the top of the disk 13 in offset relation to the axis of the shaft 11 and this block may be provided with a plurality 45 of adjustment apertures 17. In one of these apertures is mounted a pin 18 whose ends are journaled in a pair of ears 19 that straddle the block 16 and which depend downwardly from a strap 20 that is appropriately clamped to the 50 lower end of a mercury tube switch 21.

The lower end of the switch is formed by a hollow metallic cylinder 22 whose bottom end is closed and gripped by the metallic strap 20. A sleeve of insulating material 23 fits closely within 55

the upper end of the cylinder 22 and extends downwardly to a point adjacent the bottom thereto. Fitting closely within the sleeve 23 is the cylindrical portion of an upper metallic member 24 that is appropriately encircled and clamped by a metallic strap 25. The cylinder 22 and member 24 constitute the electrodes of the mercury switch which, when the switch is occupying the position illustrated in Fig. 1, are electrically connected by a globule of mercury 26. The lower end of the member 24 may terminate flush with the lower end of the sleeve 23 and a breaker ring 26a fills the space between the ends of the sleeve and member, and the bottom end of the cylinder. The inner wall forms a continuation of the inner wall of the member 24 and is preferably composed of a suitable refractory material in order to withstand the intense heat of any arcing.

20 The mercury switch per se forms no part of the present invention, and its illustration in detail is not to be regarded as restricting the use of the invention to the particular switch shown. Other types of fluid flow switches may be employed as desired for this modification and those presently described.

A pair of spaced ears 27 project upwardly from the top of the member 25 and bridged between these ears is a pin 28 that is encircled by one end of a helical spring 29 whose opposite end is secured to a screw 30 that is threaded through the upper end of a post 31. The screw 30 may be adjusted endwise to establish any desired tension in the spring and this adjustment may be held by lock nuts 32. The post 31 projects upwardly from the disk 13 and is fixed in position relative thereto by means of a cap screw 33 which is appropriately insulated from the disk, as is also the post.

40 The post 31 is located on the opposite side of the axis of the shaft 11 from the switch and, in addition to serving as a fastening support for the spring 29, also acts as a counterbalance weight for the switch 21 and prevents any whipping tendency of the disk 13 which would otherwise introduce disturbing force factors in the operation of the switch. The weight of the post and the radial distance of its center of gravity from the axis of the shaft are so related with reference to the similar characteristics of the switch 21 that the desired counterbalancing effect is obtained.

An electric cable 34 has one end fastened to the strap 20 and the opposite end to a collector ring 35, while a similar cable 36 has its opposite ends secured to the strap 25 and a collector ring 37, respectively. The rings are spaced from each other, as indicated in Fig. 1, and encircle an insulating sleeve 38 which is mounted on the hub 14. The lower ends of the cables extend downwardly through a cavity 39 provided in the hub and then outwardly through appropriate apertures in the hub and the sleeve 38 for attachment to the indicated collector rings. Accordingly, when the switch is occupying the position illustrated in Fig. 1, the rings 35 and 37 are electrically connected through the cable 34, strap 20, cylinder 22, mercury 26, member 24, strap 25, and cable 36.

70 The rings 35 and 37 are constantly engaged by the protruding ends of a pair of wipers 40 and 41, respectively, which are slidably mounted within a pair of metallic sleeves 42 and 43, respectively, provided in a casing 44 that is preferably composed of insulating material. The wipers 40 and

41 are held against the indicated rings by means of a pair of coil springs 45 and 46, respectively, which additionally bear against metallic cap plates 47 and 48, respectively. The casing 44 may be carried on an arm 49 that is supported by a bracket 50 that may be attached to any convenient part (not shown).

The cap plates 47 and 48 may be connected by wires 51 and 52, respectively, to a circuit (not shown) forming part of the device whose speed it is desired to control.

The major features of my centrifugal control may be enclosed by a cylindrical casing 56 having a cover 57 which is retained in position by a pair of long cap screws 58 that extend through the cover and are threaded in the disk 13.

In describing the operation of the control as above set forth, it will be assumed that the shaft 11 constitutes the shaft of a series motor, which is started under load, and that it is desired to regulate the speed of the motor within narrow limits.

At the instant of starting, the mercury switch 21 occupies the position illustrated in Fig. 1, that is, with its longitudinal axis substantially parallel to the axis of the shaft 11, although it will be understood that the screw 30 may be adjusted so as to incline the upper end of the switch towards the shaft axis in the general manner hereinafter described for modified types of the control.

As the speed of rotation of the shaft increases, the mercury switch 21 swings outwardly due to centrifugal force and against the tensional pull of the spring 29. Eventually, the switch is moved to a position in which the mercury globule 26 is moved upwardly along the inclined, outer surface of the member 24 by the centrifugal force to an extent sufficient to break the electric circuit between the electrodes of the switch. Immediately, the motor armature begins to decrease in speed, thus decreasing the centrifugal force and enabling the spring 29 to retract the switch inwardly towards its original position. This action enables the mercury to again complete the circuit between the electrodes and thus re-establish the current through the motor.

The principal factors which are operating during the foregoing action are centrifugal force, centrifugal force exemplified by the pull of the spring 29, the force of gravity, the cohesion and surface tension of the mercury and the action of the mercury on the variable inclined surface provided by the electrode 24. The numerical value of the centrifugal force acting on the switch at any instant is determined approximately by the weight and velocity of the switch in accordance with the following formula:

$$F = \frac{WV^2}{GR}$$

in which F is the centrifugal force, W is the weight of the mercury switch tube, V is the linear velocity of the center of gravity of the switch, G is the acceleration of gravity, and R is the radius of the center of gravity of the switch from the axis of the motor shaft. This formula is approximate for the switch tube due to the fact that the tube is tied at one end, but is substantially accurate for the globule of mercury owing to its freedom of movement.

Due to the restraint exerted by the spring 29 on the free end of the switch tube, the tube is always subjected to a retracting force which is independent of centrifugal action and which is available to retract the switch as soon as the

circuit through the motor is broken and the latter begins to reduce in speed. The practical effect of this condition is that a motor which is speed governed by this control is entirely free of the ⁵jerky action which would characterize a control having a mercury switch that was fixed in position. In the latter case, the mercury would be shifted to the top end of the switch and would be retained there until the motor had decreased in speed sufficiently to enable the mercury to ¹⁰return to a circuit making position. The heavy impulse then exerted by the electric current would frequently cause the motor to exceed the desired speed, so that the mercury would be again thrown ¹⁵towards the upper end of the switch, the circuit broken, and the foregoing action then repeated. Close speed regulation under these conditions is obviously impossible.

In my control, while the action within the switch at high speeds cannot be observed, it is considered that the probable situation is that the mercury is forced by centrifugal action into intimate contact with the outer surface of the electrode ²⁰24 and assumes an elongated shape, rather than the natural mercurial globule. This flattened and elongated shape gradually creeps upwardly along the wall of the electrode ²⁵24 until, at the controlled speed, as determined by the setting and number of coils in the spring ²⁹29 and the radial distance of the pin ¹⁸18 from the axis of the shaft, the lower end of this flattened shape breaks contact with the electrode ³⁰22. Immediately, the spring ²⁹29, as the motor decreases very slightly in speed, draws the switch inwardly and the circuit is again completed through the switch. This action is repeated within a narrow speed band which includes the desired speed and, in essence, the situation is such that a high frequency succession of circuit interruptions is obtained substantially at the controlled speed.

In the vertical application of the control, as shown, the force of gravity acting on the mercury plays a very important part in the operation of the device, as does the natural cohesion and surface tension of the mercury. Moreover, as the motor increases in speed from a starting condition, it is obvious that, as the switch pivots outwardly, the numerical value of the centrifugal force operating on the switch per se increases, ⁴⁵due to the increasing radius of the center of gravity of the switch from the axis of the motor and the increasing linear velocity of the center of gravity of the switch. The same condition holds true with respect to the mercury itself, ⁵⁰since as it moves upwardly along the wall of the electrode ⁵⁵24, its center of gravity moves farther from the axis of the motor shaft.

The control may be finely governed by varying the pivot position of the switch with reference to the shaft ⁶⁰11 and by regulating the initial tension of the spring ²⁹29. A further controlling factor may be introduced by suitably conditioning the wall of the switch electrode ⁶⁵24, i. e., providing this wall with a rough or a smooth surface in order to increase or decrease the facility with which the mercury may move along the wall.

Referring to Figs. 3 and 4, there is illustrated a modification of my improved control which employs a pivoted, counterbalance member, as contrasted with the fixed member in Fig. 1, and, further, in which the counterbalance member is used to complete the electrical circuit through the control.

Referring to Fig. 3, the numeral ⁷⁰59 designates a hub having integrally formed therewith a pair

of oppositely extending arms ⁵60 and which is preferably composed of suitable insulating material. The hub is pinned to a spindle ⁶¹whose lower end is pinned or otherwise secured to a shaft ⁶², which may be the shaft of a motor or, generally, any rotary member. The upper end of the spindle ⁶¹is journaled in the top of a casing ⁶³which encloses the parts presently described.

A pivot pin ¹⁰64 extends through the left arm ¹⁰60, as viewed in Figs. 3 and 4, and straddling this arm is a pair of ears ¹⁵65 which are rotatably supported on the exposed ends of the pin ¹⁵64. The ears ¹⁵65 depend from a metallic strap ¹⁵66 which is clamped around the lower end of a mercury tube ²⁰switch ¹⁵67 and, specifically, around the lower cylindrical electrode ²⁰68. The construction of this tube switch may be and, for purpose of illustration, will be deemed to be identical with that illustrated in Fig. 1, except for a breaker ring ²⁵similar to the ring ²⁵26 in Fig. 1, although such a ring may be used with this embodiment. Accordingly, the switch will comprise, in addition to the lower electrode ²⁵68, an upper electrode ²⁵69 that is insulated from the electrode ²⁵68, and a globule ²⁵of mercury ²⁵70, for electrically connecting the electrodes.

The upper end of the electrode ²⁵69 is encircled and clamped by a metallic strap ³⁰71 having an upwardly extending ear ³⁰72 to which is secured one ³⁰end of a helical spring ³⁵73 whose opposite end is secured to a nut ³⁵74 that is mounted on the spindle ⁶¹.

In the opposite arm ³⁵60 is mounted a pin ⁴⁰75, and a pair of spaced ears ⁴⁰76 embrace the opposite ⁴⁵sides of the arm and are journaled on the ends of the pin. The ears ⁴⁵76 depend from a metallic strap ⁴⁵77 which is clamped around the lower end of a metallic, counterbalance member ⁴⁵78 whose upper end is clamped by a metallic strap ⁴⁵79. ⁵⁰This strap is provided with an upwardly extending ear ⁵⁰80, and fastened thereto is one end of a helical spring ⁵⁵81 whose opposite end is attached to the nut ⁵⁵74. The distribution of mass in the member ⁵⁵78 approximates that in the switch ⁵⁵67, ⁶⁰and the radial distances of the centers of gravity of these parts from the spindle ⁶¹are the same at all times so that, at high speeds, the spindle ⁶¹will rotate without whipping.

The straps ⁵⁵77 and ⁶⁰79 are electrically connected by a cable ⁶⁵82 and one end of a wire ⁶⁵83 is coiled around and in electrical connection with the pin ⁶⁵64, the opposite end of the wire being secured to a collector ring ⁶⁵84 that encircles and is embedded in the hub ⁶⁵59. The intermediate portion ⁶⁵of the wire ⁶⁵83 extends through the body of the hub. Similarly, one end of a wire ⁷⁰85 is wound around and in electrical contact with the pin ⁷⁰75 and this wire is then led through the body of the hub ⁷⁰59 for affixation to a collector ring ⁷⁰86 which ⁷⁵also encircles the hub. The collector rings occupy the spaced relation illustrated in Fig. 3 and are in electrical communication through the control by means of the wire ⁷⁵83, pin ⁷⁵64, ears ⁷⁵65, mercury switch ⁷⁵67 (when the mercury ⁷⁵70 is occupying ⁸⁰the position illustrated in Fig. 3), strap ⁷⁵71, cable ⁷⁵82, strap ⁷⁵79, member ⁷⁵78, strap ⁷⁵77, ears ⁷⁵76, pin ⁷⁵75, and wire ⁷⁵85.

A pair of metallic wipers ⁷⁵87 and ⁸⁰88 are slidably mounted in a casing ⁸⁰89 formed of insulating ⁸⁵material and appropriately carried by the casing ⁸⁵63 and the outer ends of these wipers are pressed constantly against the collector rings ⁸⁵84 and ⁸⁵86, respectively, by means of a pair of coil springs ⁹⁰92 and ⁹⁰93, respectively, which are mounted in ⁹⁵75

recesses in the casing 89. Metallic stems 90 and 91 are connected to the wipers 87 and 88, respectively, and extend externally of the casing 89 for connection to an electric circuit.

5 When the control is rotating at relatively low speeds, the lower ends of the switch 67 and member 78 rest on and are in electrical contact with a shorting ring 94 which is mounted on the upper end of the hub 59. This ring is electrically connected to the wire 85 by a wire 94. Accordingly, when the circuit is completed through the control, the current is short-circuited through the ring until the control attains a speed of rotation at which the mercury 10 switch swings outward.

The operation of the control illustrated in Fig. 3, so far as the mercury switch is concerned, is identical with that heretofore described except that, due to the retention of a globule of mercury 20 beneath the shoulder formed by the lower ends of the insulating sleeve and electrode 69, the make and break of the switch is between globules of mercury. It will be understood that the spring 73 may be provided with any desired 25 initial tension in order to secure the required operation of the control. The principal distinction between this modification and the one heretofore described resides in the use of the pivoted counterbalance member 78 as a path for the flow 30 of the electric current through the control.

In Figs. 5 to 9, inclusive, there is illustrated a further modification of my control which is also characterized by the use of a pivoted counterbalance member, but is distinguished from the 25 preceding embodiment in that this member is not employed as a part of the electric circuit through the control and also by the use of a different arrangement of spring action.

Referring to Fig. 5, the numeral 95 designates 40 a shaft which may be a motor shaft, or the shaft of any rotary machine, or a shaft which is connected to either a motor or a machine, and which extends through and is journaled in a bearing 96 formed in the bottom plate of the 45 control casing 97. The upper end of the shaft 95 may be squared to fit within and drivably connect a cross-shaped plate 98 having the oppositely extending arms 99 and 100, and 101 and 102, respectively. The plate 98 rests upon a disk 50 103 which in turn is supported on a spacer 104 that rests on the upper end of the bearing 96. Preferably, the plate 98, disk 103, and spacer 104 are formed of a suitable insulating material.

At a determined radial distance from the axis 55 of the shaft 95, a pin 105 is mounted in the arm 99 and embracing the sides of this arm and journaled on the ends of the pin is a pair of ears 106 that depend from a metallic strap 107 which 60 clamps the metallic lower end 108 of a mercury switch 109. The upper end of the switch is formed by a metallic part 110 and it will be understood that, for purpose of illustration, the switch 109 may be identical in construction with those illustrated in Fig. 1 or 3, or in other words, 65 that the parts 108 and 110 constitute the electrodes of the switch which are insulated from each other and, when the switch is occupying the position illustrated in Fig. 5, are electrically connected by a mass of mercury 111. In Fig. 5, 70 it will be noted that the axis of the mercury tube switch is inclined to the axis of the shaft 95, the upper end of the switch being closer to the shaft than the lower end.

The strap 107 is electrically connected by a 75 cable 112 to a cap screw 113 that extends down-

wardly through the arm 99 and disk 103 for threaded engagement with an annular, collector ring 114. A similar cap screw extends through the arm 100 for engagement with the ring 114.

A pin 115 is also mounted in the arm 100 at the same radial distance from the axis of the shaft 95 as is the pin 105 and embracing the sides of this arm is a pair of ears 116 in which are journaled the ends of the pin 115. These ears depend from a strap 117 which clamps the lower 10 end of a counterbalance member 118. The function of this member is identical with the other counterbalance members heretofore described, except that, in the present instance, the member 118 acts solely as a counterbalance and not as a 15 path for the electric current through the control. When the control is at rest, the axis of the member 118 makes the same angle with the axis of the shaft 95 as does the axis of the mercury switch 109 and the inner edges of these parts 20 20 may rest upon a metallic, shorting plate 119 that extends along the top surfaces of the arms 101 and 102.

A slightly different form of spring restraint is employed in this control modification and it 25 takes the form of a pair of U-shaped spring members which are formed of flat spring metal and which are located at the ends of the arms 101 and 102, respectively, or on opposite sides of the plane in which the switch and counter- 30 balance member swing. These springs are identical in construction, so that it is only necessary to describe one of them in detail.

The member generally is denoted by the numeral 120 in Fig. 6 and it includes a base 121 35 that is received within a recess 122 that is notched on the underside of the extremity of the arm 101 (see Figs. 8 and 9) and it rests directly upon the top surface of the disk 103. The spring arms 123 and 124 extend freely upwardly 40 from the base 121 and their upper ends are curved outwardly and then downwardly into a substantially spiral formation and are attached, respectively, to metallic straps 125 and 126 which clamp the switch electrode 110 and the upper 45 end of the counterbalance member 118, respectively.

Accordingly, as the switch and counterbalance member move outwardly under the impulse of centrifugal force, they are at all times subject 50 to the resilient restraint imposed by the spring arms 123 and 124, including their spiral end formations.

As the spring arms 123 and 124 move outwardly and inwardly they are guided by and have electrical contact with the walls of recesses 127 provided in the opposite ends of a thin, guide plate 128 which is adjustably mounted on a threaded stem 129 that extends downwardly through the arm 101 and also through the base 121 of the 60 spring member, the disk 103, and is finally threaded in an annular, collecting ring 130 which abuts against the underside of the disk in spaced relation to the collector ring 114. The vertical position of the guide plate 128 may be maintained 65 by top and bottom lock nuts 131 (see Fig. 9). A similar spring arrangement and guide control extends upwardly from the arm 102 and the vertical rigidity and spacing of the threaded stems 129 is maintained by a strut 132 that extends between the mercury switch and counterbalance member and has its ends fastened to the upper 70 ends of the stems.

The under surfaces of the collector rings 114 and 130 are constantly engaged by wipers 133 75

and 134, respectively, which are appropriately insulated from each other and held against their respective collector rings by springs 135 and 136. Wires 137 and 138 extend outwardly from the 5 wipers 133 and 134, respectively, for connection to any desired electrical circuit.

When the parts are in the several positions illustrated in Fig. 5, electrical connection between the collector rings through the control is obtained by means of the cap screw 113, cable 112, 10 strap 107, switch 109, clamp 125, spring arm 123, guide plate 128, and stem 129.

The operation of the embodiment illustrated in Fig. 5 will be apparent from the foregoing description. As far as the mercury switch action is concerned, it is substantially identical with that illustrated in Fig. 1, except that the initially inclined position of the switch makes it possible to provide for a delayed interruption of the associated circuit at any given speed, dependent upon the setting and strength of the springs 120. Moreover, the member 118 operates solely as a counterbalance weight. As in the case of the modification shown in Fig. 3, the current through 20 the control is short-circuited through the plate 119 when the control is rotating at relatively low speeds and this circuit is not opened until the mercury switch swings outward, whereupon the current passes through the switch. As clearly 25 illustrated in Fig. 9, the plate 119 is electrically connected to the ring 130 by the stems 129.

In Figs. 10 to 12, inclusive, there is illustrated a further modification of my improved centrifugal control which differs from that illustrated 30 in Fig. 5 in that the counterbalance member is used as a part of the electric circuit through the control and also, most importantly, in the type of spring restraint which is imposed upon the parts of the control that are moved under the 35 impulse of centrifugal force. As already described, the other types of control employ either helical or simple flat springs, whereas the type of control now under discussion utilizes the torsional action of flat spring members which are 40 held at their ends and twisted at their intermediate portions.

Referring to Fig. 10, the number 139 designates a shaft generally which is subjected to a motion of rotation and whose upper end is secured to an 45 encircling sleeve 140 that is received within a counterbore provided in the hub portion of a disk 141 that is preferably composed of insulating material. The shaft 139 is also pinned to this hub.

On the top surface of the disk 141 is mounted 50 a pair of spaced cap screws 142 and bridged between these screws and with its ends secured thereto is a flat metallic strip 143 composed of any suitable springy metal. This strip is offset 55 from the axis of the shaft 139. A threaded stem 144 extends downwardly through the strip 143 midway of its ends and this stem depends from the underside of a metallic, sleeve socket 145 which receives the metallic, lower end 146 of a 60 mercury tube switch 148. A sleeve nut 147 encircles the socket 145 and frictionally retains the lower end of the switch in position. The lower end member 146 constitutes one of the electrodes 65 of the switch and the other electrode is constituted by an upper end member 149, the entire construction of the switch being similar, for example, to the mercury switches illustrated in Fig. 1 or 3. When the switch is occupying the 70 inclined position relative to the axis of the shaft 75

139, as illustrated in Fig. 10, the electrodes are electrically connected by a mass of mercury 150.

One of the cap screws 142, and accordingly the electrode 146, is electrically connected by a cable 151 which extends downwardly through the insulating disk 141 for securement to a collector ring 152 that encircles the hub portion of the disk. The other electrode member 149 is electrically connected by a cable 153 to the top end of a metallic, counterbalance member 154 having a threaded stem that extends downwardly through the intermediate portion of a flat, metallic, spring strip 156 whose ends are supported on a pair of cap screws 157 that are threaded in the disk 141. As clearly indicated in Fig. 11, the screws 142 and 157 are so positioned that the strips 143 and 156 are located on opposite sides of the axis of the shaft 139 and parallel to each other, thus insuring that the substantially pivotal connection of the mercury switch and counterbalance member to their respective spring strips are at the same radial distance from the axis of the shaft 139.

One of the cap screws 157 is electrically connected by a cable 158 that extends downwardly 25 through the disk 141 for securement to a collector ring 159 that encircles the hub of the disk in spaced relation to the ring 152.

The peripheral surfaces of the rings 152 and 30 159 are constantly engaged by the ends of a pair of wipers 160 and 161, respectively, which are 35 slidably mounted in metallic sleeves 162 and 163, respectively. These sleeves are carried by an insulating casing 164 that is attached to a bracket 165 which in turn may be supported by any external structure, such as the frame of a motor (not shown). The wipers 160 and 161 are 40 yielding forced outwardly by coil springs 166 and 167, respectively, which are abutted by screws 168 and 169, respectively. Wires 170 and 171 are 45 electrically connected to the screws 168 and 169, respectively, and may be connected to any desired electric circuit. The centrifugally operated portions of my control may be enclosed within a casing 172 that is suitably carried by the disk 45 141.

The action of the mercury switch 148 in this particular modification is substantially identical with those heretofore described, the principal distinction in this type of control residing in the 50 nature of the spring restraint which is provided by the torsional energy stored in the spring strips 143 and 156 as they are twisted by the outward swinging movement of the switch 148 and counterbalance 154. The springs 143 and 156 also act 55 to return the switch and counterbalance to the positions shown in Fig. 10.

It will be understood that any of the modifications illustrated in Figs. 1, 3, 5 and 10 may be arranged to "make" associated electrical circuits 60 by inverting the positions of the mercury switches and, also, that any of the indicated modifications may be horizontally disposed when used with a horizontal shaft. Further, any of the modifications may be connected to a rotary machine, generally speaking, for the purpose of controlling the speed of the particular machine, or for controlling the operation of other apparatus, or electrical circuits, which it is desired to control in reference to the speed of the machine with which 70 the control is connected. Associate electrical circuits may be "made" or "broken" by this type of control with equal facility.

For example, where employed to control the speed of electric motors, the primary circuit of 75

the motor may be interrupted for this purpose, or the circuit through the field coils may be broken, or the control may introduce a resistance in either the primary circuit or the field coils, or both, at any determined speed of rotation of the motor shaft. Because of its extreme sensitivity my control is particularly useful in the speed governing of alternating current motors, and for this purpose, it may be used to cut out the resistance in the rotor circuit of such a motor which is started under load and which resistance it is desired to cut out after the motor attains speed; or an alternating current motor may be started as an induction motor and at some determined speed, the control may be arranged to change this motor over to a synchronous motor.

The primary advantage of my control is due to subjecting the mercury switch at all times to a spring tension and which enables the controlled apparatus to operate with an entire absence of any jerky or dampening action that would otherwise result in an extreme case of "hunting". Any desired range of control may be freely exercised by suitably conditioning the spring tension, the initial radial distance of the axis of the mercury tube switch from the axis of the operating shaft, the initial inclination of the switch relative to this shaft, and by varying the character of the internal surface of the switch along which the mercury globule moves, i. e., by roughening or smoothing this surface, or otherwise conditioning the same so as to affect the movement of the mercury. The control is particularly useful in closely regulating the speed of an electric motor having a light armature because of the non-uniform acceleration and deceleration characteristic of this rotary part.

Where the conditions of operation require an inclination of the axis of the switch relative to the rotating shaft, an inclination of the switch tube of approximately 10 degrees has been found to be suitable, although this angle may be varied as desired. The switch tube may be moved outwardly until its inclination may vary from 6 degrees to 10 degrees and at this particular inclination one installation has been observed to make and break the associated electrical circuit at approximately 1200 times per minute, the free end of the switch tube oscillating approximately $\frac{1}{2}$ of an inch to $\frac{1}{4}$ of an inch at the indicated inclination. Under these conditions, the motor ran smoothly without hunting. The control is capable of being operated on alternating or direct current and in the case of alternating current, oscillograph tests have indicated that the mercury switch closes for a time duration of approximately six cycles and remains open for an equivalent period on an alternating current having a frequency of 60 cycles. Where direct current is employed, no spark quenching condensers or resistances are necessary in order to eliminate objectionable sparking within the switch during the rapid makes and breaks.

I claim:

- 65 1. A centrifugal control comprising a rotary part, a fluid flow switch mounted on the part to swing and reposition the fluid relative to at least one of the electrodes of the switch by the action of centrifugal force, and resilient means for yieldingly restraining the movement of the switch.
- 70 2. A centrifugal control comprising a rotary part, a fluid flow switch mounted on the part to swing and reposition the fluid relative to at least one of the electrodes of the switch by the action of centrifugal force, and means independent of

centrifugal force for assisting in determining the position of the switch at any rotative speed of the part.

3. A centrifugal control comprising a rotary part, a fluid flow switch shiftable on the part under the impulse of centrifugal force between positions corresponding to the making and breaking of an associated electric circuit, and yielding means acting to return the switch to one of the positions as the force decreases. 10

4. A centrifugal control comprising a rotary part, and a fluid flow switch bodily shiftable on the part under impulse of centrifugal force between positions making and breaking an associated electric circuit, the switch being biased to one of the positions. 15

5. A centrifugal control comprising a rotary part, a fluid flow switch mounted on the part to swing and reposition the fluid relative to at least one of the electrodes of the switch by the action of centrifugal force, means for adjusting the radial distance of the switch support from the axis of the part to vary the force effect on the switch, and resilient means for yieldingly restraining the movement of the switch. 20 25

6. A centrifugal control comprising a rotary part, a fluid flow tube switch pivoted at one end on the part to rock and reposition the fluid relative to at least one of the electrodes of the switch by the action of centrifugal force, and a spring connecting the part and the free end of the switch. 30

7. A centrifugal control comprising a rotary part, a fluid flow tube switch pivoted at one end on the part to rock and reposition the fluid relative to at least one of the electrodes of the switch by the action of centrifugal force, the switch being offset from the axis of the part, and a spring connecting the part and the free end of the switch. 35 40

8. A centrifugal control comprising a rotary part, a fluid flow tube switch pivoted on the part to rock an end between inner and outer positions relative to the axis of the part and reposition the fluid relative to at least one of the electrodes of the switch, and resilient means for biasing the switch in the inner position. 45

9. A centrifugal control comprising a rotary part, a fluid flow tube switch pivoted on the part to rock under the impulse of centrifugal force and thereby reposition the fluid relative to at least one of the electrodes of the switch, and a spring connecting the part and a free end of the switch, the axes of the spring and switch being substantially normal in all positions of the switch. 50 55

10. A centrifugal control comprising a rotary part, a fluid flow tube switch pivoted on the part in offset relation to the axis of the shaft to rock under the impulse of centrifugal force and thereby reposition the fluid relative to at least one of the electrodes of the switch, a fixed counterbalance member mounted on the part in opposing, diametral relation to the switch, and a spring connecting the part and a free end of the switch. 60 65

11. A centrifugal control comprising a rotary part, a fluid flow tube switch pivoted on the part in offset relation to the axis of the part to rock under the impulse of centrifugal force and thereby reposition the fluid relative to at least one of the electrodes of the switch, a fixed counterbalance member mounted on the part in opposing, diametral relation to the switch, and a spring connecting the member and a free end of the switch, the axes of the spring and switch 70 75

being substantially normal in all positions of the switch.

12. A centrifugal control comprising in combination, a rotary part, a fluid flow tube switch pivoted on the part in offset relation to the axis of the part to rock under the impulse of centrifugal force and thereby reposition the fluid relative to at least one of the electrodes of the switch, a counterbalance member mounted on the part in opposing, diametral relation to the switch, a spring connecting the member and a free end of the switch, a pair of collector rings mounted on the part in insulated relation to each other and adapted for engagement by contacts forming a part of an electric circuit, and wires connecting the electrodes and rings, respectively.

13. A centrifugal control comprising a rotary part, a fluid flow tube switch pivoted on the part in offset relation to the axis of the part to rock under the impulse of centrifugal force and thereby reposition the fluid relative to at least one of the electrodes of the switch, a counterbalance member pivotally mounted on the part in opposing, diametral relation to the switch, and springs connecting the part and those ends of the switch and member, respectively, which tend to swing outwardly when the part is rotated.

14. A centrifugal control comprising in combination, a rotary part, a fluid flow tube switch pivoted on the part in offset relation to the axis of the part to rock under the impulse of centrifugal force and thereby reposition the fluid relative to at least one of the electrodes of the switch, a counterbalance member pivotally mounted on the part in opposing, diametral relation to the switch, springs connecting the part and those ends of the switch and member, respectively, which tend to swing outwardly when the part is rotated, and a pair of collector rings mounted on the part in insulated relation to each other and adapted for engagement by contacts forming a part of an electric circuit, the rings being electrically connected to the electrodes, respectively, one of the connections being through the member.

15. A centrifugal control comprising a rotary part, a fluid flow tube switch pivoted on the part in offset relation to the axis of the part to rock under the impulse of centrifugal force and thereby reposition the fluid relative to at least one of the electrodes of the switch, a counterbalance member pivotally mounted on the part in opposing, diametral relation to the switch, and flat springs fastened to the part and switch and member, respectively, for resiliently restraining the movement of the switch.

16. A centrifugal control comprising a rotary part, a fluid flow tube switch pivoted on the part in offset relation to the axis of the part to rock under the impulse of centrifugal force and thereby reposition the fluid relative to at least one of the electrodes of the switch, a counterbalance member pivotally mounted on the part in opposing, diametral relation to the switch, and a pair of U-shaped, flat spring elements located on opposite sides, respectively, of a line connecting the switch and member, each element having a pair of spring arms, the ends of the arms being spiraled and fastened to those ends of the switch and member, respectively, which tend to swing outwardly when the part is rotated.

17. A centrifugal control comprising a rotary part, a fluid flow tube switch pivoted on the part in offset relation to the axis of the part to

rock under the impulse of centrifugal force and thereby reposition the fluid relative to at least one of the electrodes of the switch, a counterbalance member pivotally mounted on the part in opposing, diametral relation to the switch, a pair of U-shaped, flat spring elements located in opposite sides, respectively, of a line connecting the switch and member, each element having a pair of spring arms whose ends are spiraled and fastened to those ends of the switch and member, respectively which tend to swing outwardly when the part is rotated, the switch spring arms being electrically connected to one of the switch electrodes, and a pair of collector rings insulated from each other mounted on the part, one ring being electrically connected to the other electrode and the other ring to the switch spring arms.

18. In a centrifugal control, the combination of a rotary part, a torsion spring carried by the part, and a fluid flow switch mounted on the spring to rock under the impulse of centrifugal force and thereby reposition the fluid relative to at least one of the electrodes of the switch, the switch rocking against the torsion action of the spring.

19. In a centrifugal control, the combination of a rotary part, a flat spring fixed at its ends to the part, and a fluid flow switch secured at one end thereof to an intermediate portion of the spring and adapted to rock and twist the spring under the impulse of centrifugal force to thereby reposition the fluid relative to at least one of the electrodes of the switch.

20. In a centrifugal control, the combination of a rotary part, a pair of parallel, flat springs fixed at their respective ends to the part on opposite sides of the axis thereof, a fluid flow tube switch and a counterbalance member each supported at one end on an intermediate portion of the springs, respectively, the switch and member being adapted to rock under the impulse of centrifugal force and twist the springs, the rocking of the switch repositioning the fluid relative to at least one of the electrodes of the switch.

21. In a centrifugal control, the combination of a rotary part, a pair of parallel, flat torsion springs fixed at their respective ends on and located on opposite sides of the axis of the part, a fluid flow tube switch supported at one end thereof on an intermediate portion of one of the springs, one of the switch electrodes being electrically connected to the switch supporting spring, a counterbalance member similarly supported on and electrically connected to the other spring, the switch and member being adapted to rock and twist the respective springs under the impulse of centrifugal force and the rocking of the switch repositioning the fluid relative to at least one of the electrodes of the switch, and a pair of collector rings mounted on the part in insulated relation to each other and adapted to be engaged by contacts forming a part of an electric circuit, the rings being electrically connected to the electrodes, respectively, one of the connections being through the member.

22. A centrifugal control comprising in combination, a rotary part, a mercury switch having a metallic end forming an electrode of the switch mounted on the part to swing under the impulse of centrifugal force between positions making and breaking an associated electric circuit, resilient means for biasing the switch in the making position, and a metallic plate engageable with the metallic end at relatively low rotative speeds of the part, the plate being connected in the cir- 75

cuit and the electric current being short-circuited through the plate until the rotary part attains a predetermined speed.

23. Means for controlling an electric circuit by the combined action of centrifugal and centripetal forces comprising a rotary member, a shiftable device mounted on the member having a guiding surface and a pair of electrodes forming a part of a circuit, a mass of current conducting fluid for bridging the electrodes, the device and fluid being relatively shiftable by centrifugal force between positions making and breaking the circuit, and centripetal acting, resilient means for restraining movement of the device.

24. A centrifugal switch comprising a member rotatable about a substantially vertical axis, a switch supporting means mounted thereon, and a fluid flow switch of the tubular type mounted

on said supporting means, at least a portion of said supporting means being movable with respect to said axis to permit the slope of said switch to change in response to centrifugal forces exerted thereon during rotation of said base.

25. A centrifugal switch comprising a member rotatable about a substantially vertical axis, a switch supporting means mounted thereon, and a fluid flow switch mounted on said supporting means, said supporting means providing a yielding support to said switch which tends to restrain movement thereof along an arc away from said axis in opposition to the centrifugal forces exerted on said switch during rotation of said base, whereby the orientation of said switch with respect to the open and closed circuit positions thereof changes with speed of rotation.

JOSEPH H. STALEY.
